DESIGN FOR A BROOCH OR SIMILAR ARTICLE

Alfeo Verrecchia, Providence, R. I.

Application June 13, 1946, Serial No. 130,682

Term of patent 3½ years

(Cl. D45—19)

To all whom it may concern:

Be it known that I, Alfeo Verrecchia, a citizen of the United States, residing at Providence, in the county of Providence and State of Rhode Island, have invented a new, original, and ornamental Design for a Brooch or Similar Article, of which the following is a specification, reference being had to the accompanying drawing forming part thereof.

Fig. 1 is a front elevational view of a brooch or similar article showing my new design, and

Fig. 2 is a side elevational view thereof.

The dominant features of the design reside in the portions shown in full lines.

I claim:

The ornamental design for a brooch or similar article, substantially as shown and described.
ALFEO VERRECCHIA.
